CLAIM

The ornamental design for a packet with integral connector tab, as shown and described.

DESCRIPTION

FIG. 1 is a perspective view of the packet with integral connector tab showing my new design; FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a perspective view of the second embodiment of the packet with integral connector tab;

FIG. 9 is a front view thereof;

FIG. 10 is a rear view thereof;

FIG. 11 is a side view thereof;

FIG. 12 is an opposite side view thereof;

FIG. 13 is a top view thereof; and,

FIG. 14 is a bottom view thereof.

(Continued)

The broken line showing of portions of the packet with integral connector tab is included for the purpose of illustrating environmental structure and forms no part of the claimed design.

1 Claim, 10 Drawing Sheets
